DESIGN FOR LEATHER OR SIMILAR
ARTICLE

Fred. A. Kolb, Newark, N. J.

Application July 14, 1936, Serial No. 63,835

Term of patent 14 years

To all whom it may concern:

Be it known that I, Fred. A. Kolb, a citizen of the United States of America and resident of Newark, in the county of Essex and State of New Jersey, have invented a new, original, and ornamental Design for Leather or Similar Article, of which the following is a specification, reference being had to the accompanying drawing, forming part thereof.

Figure 1 is a plan view of a piece of leather showing my new design enlarged two times; and

Figure 2 is a section taken on line 2—2 of Figure 1, enlarged to twice the size of Figure 1.

In the drawing is shown in dot-dash lines, a unit which embodies my new design, which unit is used as a repeat. The border line of the drawing in Fig. 1 shows an arbitrary cut of a piece of leather illustrating my new design.

I claim:

The ornamental design for leather or similar article, substantially as shown and described.

FRED. A. KOLB.
